(57) **CLAIM**

The ornamental design for a base for physical assistance devices, as shown and described.

DESCRIPTION

FIG. 1 is an isometric view of a base for physical assistance devices in accordance with the invention, the broken line showing of the remainder of the base for physical assistance device is included for the purpose of illustrating the base for physical assistance device and forms no part of the claimed design.

FIG. 2 is a front view of a base for physical assistance devices;

FIG. 3 is a right side view of a base for physical assistance devices, the left side being a mirror image of the right side;

FIG. 4 is a rear view of a base for physical assistance devices;

FIG. 5 is a bottom view of a base for physical assistance devices; and,

FIG. 6 is a top view of a base for physical assistance devices.
